UNITED STATES PATENT OFFICE.

SAMUEL C. LAY, OF RIDGEVILLE, INDIANA, AND FREDERICK M. BAKER, OF DETROIT, MICHIGAN, ASSIGNEES TO THE JOSEPH LAY COMPANY, OF RIDGEVILLE, INDIANA, A CORPORATION.

BROOM-STAPLING MACHINE.

1,275,052.

Specification of Letters Patent.

Patented Aug. 6, 1918.

Original application filed February 12, 1917, Serial No. 148,132. Divided and this application filed April 19, 1918. Serial No. 229,524.

To all whom it may concern:

Be it known that we, SAMUEL C. LAY and FREDERICK M. BAKER, citizens of the United States, and residents of Ridgeville and Detroit, respectively, counties of Randolph and Wayne, respectively, and States of Indiana and Michigan, respectively, have invented a certain new and useful Broom-Stapling Machine; and we do hereby declare that the following is a full, clear, and exact description thereof, reference being had to the accompanying drawings, in which like letters refer to like parts.

This invention relates to work supports for broom stapling machines, and is a division of our former application, Serial No. 148,132, filed February 12, 1917, for broom stapling machine.

The prime feature of the invention is the means for elevating the work supporting table so as to rest a broom head in position to engage the staple driving mechanism which comprises a sliding frame having a curved surface for coöperation with the curved surfaces upon the uprights on which the frame operates.

A further feature of the invention is the provision of automatically operated means for giving lateral swinging movement to the frame, whereby the curved surfaces thereof will be caused to travel over the curved surfaces of the uprights to move the frame and work supporting table attached thereto upwardly or downwardly. A further feature of the invention is the provision of yielding parts employed for moving the sliding frame back and forth, so that when a thicker broom head is placed upon the table and moved into engagement with the stapling mechanism, the operating parts employed for raising the table will yield to compensate for the thicker broom head. Other objects and advantages will be hereinafter more fully set forth.

The full nature of the invention will be understood from the accompanying drawings and the following description and claims:

Figure 1 is an end elevation of a broom stapling machine showing the work supporting means attached thereto. Fig. 2 is a side elevation thereof showing the work support in its lowered position. Fig. 3 is a

detail side elevation of the machine showing the work table in elevated position and Fig. 5 is an enlarged sectional view as seen on line 4—4 of Fig. 1. Fig. 5 is a longitudinal sectional view through the rod employed for moving the work support or table into position.

Referring to the drawings in which similar reference numerals designate corresponding parts throughout the several views, 10 indicates a supporting base upon which is mounted an upright frame 11, and upon the upper portion of the frame 11 are bearings 12 through which the shaft 13 extends, said shaft being connected at one end to the driving wheel 14 through a clutch mechanism 15 of the ordinary construction, and by means of which the driving wheel 14 is thrown into and out of operation with the shaft 13.

Adjacent the lower portion of the machine is a foot lever 16 which is secured to a shaft 17, and on said shaft 17 is secured a lever 18 extending within the base 10. Pivoted to the end of the lever 18 is a rod 19 which is connected at its upper end to the clutch mechanism 15 for operating said clutch mechanism, whereby the operation of the machine may be manually controlled.

Secured to the shaft 13 is a gear 20 which drives a chain 21, said chain passing around an idler 23, a gear 22 and around a gear 24 on the shaft 25 mounted in the base 10, and then back to the gear 20.

In broom stapling devices of this class, it is necessary to provide a work support for holding the broom head while the staple is being driven therethrough and clenched, and it is also necessary to provide means for raising and lowering the work support so as to bring the work adjacent the end of the staple driving device when the staple is being driven therethrough, and then lowering the work support so that a new broom head may be placed upon the work support, or the position thereof changed to receive an additional staple. To this end therefore, a standard 79 is mounted upon a portion of the base 10, said standard having adjacent its lower end lateral extensions 79^a, the upper edges 77 thereof being concave. The standard 79 is provided with a vertical bore 79^b, in which is vertically slidable a shaft 79^c, and fixed to the upper end of said shaft

is a work or broom supporting table 78, said work table being movable upwardly or downwardly to adjust the broom head 82, shown by dotted lines in Fig. 4, toward or 5 from the staple driving extension 81.

The work supporting table is automatically raised or lowered by pivotally attaching frame members 75 to the support 78. The lower ends 77^a of the frame members 10 have convex surfaces which slide over and cooperate with the curved ends 77 of the extensions 79^a, and as the trend of said curved surfaces are at a tangent to a plane extending horizontally of the frame members, the supporting member 78 will be raised when the frame members 75 are swung outwardly, and will be lowered when the frame members are swung inwardly.

The frame members 75 are swung laterally to raise or lower the member 78 through the medium of a rod 74 which is pivoted to the inner edges of the frame members, and is pivoted at its opposite end to the lever 70, the lower end of said lever being pivoted to 25 the base 10 in any suitable manner. The lever 70 is provided with an inwardly extending roller or stud 71, which enters a camway 72 in the face of the drum 73, said drum being fixed to the shaft 25 and is 30 driven thereby.

As broom heads of varying thicknesses are operated upon and as it is necessary to compensate for the thicker broom heads, the rod 74, employed for moving the frame members 75, is formed in two sections 74^a and 74^b, the part 74^a being tubular and telescoping with the other part. The rod 74 is normally held rigid so that the support 78 will be elevated a sufficient height to bring 40 the thinnest broom heads operated upon in proper position to receive the staple by means of a spring 74^c which surrounds the rod 74 and the ends thereof abut against shoulders on the parts 74^a and 74^b, respectively. As the lever 70 moves the same distance forwardly regardless of the thickness of the broom head, the spring 74^c will be compressed when a thicker broom head is placed upon the table so that while the lever 50 70 makes the same movement each time, the table 78 is not moved to the same height, depending upon the thickness of the broom head. The telescoping movement of the parts of the rod 74 are limited by providing 55 slots 74^d in the part 74^a through which project the ends of a pin 74^e carried by the part 74^b. It will also be noted by referring to Fig. 3 that the cam slot 72 has a straight portion into which the roller 71 enters as the 60 lever 70 has completed its outward stroke, thereby holding said lever stationary while the stapling operation is being performed.

In operating the device, supposing the parts to be in the position shown in Figs. 1 65 and 2 of the drawing, a broom head is

placed upon the work support 78 and properly positioned to receive a staple 90, when downward pressure is applied to the free end of the foot lever, thereby operating the clutch mechanism 15 to apply rotating power 70 to the shaft 13.

As the shaft 13 rotates, power is applied to the shaft 25, and drum 73 thereon through the medium of the driving chain 21 and as the drum 73 rotates, the roller 71 will travel 75 in the cam slot 72 and throw the upper end of the lever 70 outwardly, thus directing outward pressure on the frame member 75 and owing to the curved ends 77 and 77^a, the work support and the broom head resting 80 thereon will be moved upwardly and in position to receive the staple 90 as it is driven downwardly by the extension 81, said staple being driven entirely through the broom head and the free ends thereof clenched as 85 shown in Fig. 4.

The extension 81 is also operated from the shaft 13 by attaching to one end of the shaft a cam 41 to which is attached a pivot pin 49, upon which is mounted a connecting rod 90 50, said rod being coupled to a hammer 51 by means of a wrist pin 52 and to the lower end of the hammer 51 is connected the driving extension 81, and as the driving hammer 51 reciprocates through a bearing 53, 95 the extension 81 will always be in position to engage and drive the staple.

Coincident to the completion of the downward stroke of the hammer 51 and extension 81, the drum 73 will have turned a sufficient 100 distance to cause the lever 70 to again move inwardly, thereby lowering the work support 78, so that the broom head may be positioned to receive an additional staple or a new broom head placed thereon. As soon 105 as the broom head has been properly positioned on the support 78, the foot lever 16 is again operated and the stapling operation repeated.

The invention claimed is:—

1. A work supporting means for stapling machines, comprising the combination with a frame, and a staple driving means thereon, of a standard mounted on said frame, a shaft vertically slidable in said standard, a work supporting member carried by said standard, frame members pivoted to said work supporting member having convex lower edges, extensions having concave upper edges to receive the convex edges of the frame members, the center of curvature of the curved portions being displaced from the axis of vertical motion, and means for automatically swinging the frame members back and forth, whereby the work supporting member will be raised or lowered by the action of the curved portions of the frame members and extensions.

2. A work supporting means for stapling machines, comprising the combination with

a frame, and a staple driving mechanism mounted thereon, of a standard carried by the frame, a work supporting table movably mounted on the standard, a frame member at each side of the standard having its upper end pivoted to the work supporting member, the lower end of each frame having a convex curvature, lateral extensions at the lower end of the standard having concave upper edges for coöperation with the curved ends of the frame members, the center of curvature of the curved portions being displaced from the axis of vertical motion, and means to swing said frame members laterally to raise or lower the work supporting member.

3. The combination with a frame, and a staple driving mechanism thereon, of a work supporting mechanism comprising a work table, a shaft attached to the work table, a standard on said frame in which said shaft is vertically slidable, a pair of frame members pivoted at their upper ends to said work supporting table, said frame members having their lower ends convexly curved, extensions on the standard having their upper edges concavely curved and adapted to receive the curved ends of the frame members, the center of curvature of the curved portions being displaced from the axis of vertical motion, a drum having a camway therein, means to rotate said drum, a pivotally mounted lever, a roller on said lever entering said camway and adapted to travel therein, and a rod connecting the upper end of said lever with said frame members, whereby when said lever is swung back and forth the frame members

will be operated to raise or lower the work supporting table.

4. The combination with a broom stapling device, including a frame and staple driving mechanism thereon, of a work supporting table, a shaft depending from said table, a standard on the frame having a socket to receive said shaft, extensions on said standard having their upper edges concave and inclined to displace the center of curvature thereof from the axis of vertical motion, frame members pivoted to the work carrying table having their lower ends convex and inclined to displace the center of curvature thereof from the axis of vertical motion, and adapted to coöperate with the inclined concave edge of the extensions, and means to swing said frame members laterally of the work supporting table, whereby the table will be moved toward or from the staple driving means.

5. The combination with a work supporting table, and frame members pivoted to said table adapted to be moved laterally to raise or lower the table, of a pivotally mounted lever, a drum having a camway therein, a roller on said lever entering said camway, means to rotate the drum and rock said lever back and forth, a two-part telescoping rod connecting the upper end of said lever and said frame members, and yielding means for normally holding the parts of the rod fully extended.

In witness whereof we have hereunto affixed our signatures.

SAMUEL C. LAY.
FREDERICK M. BAKER.
